UNITED STATES PATENT OFFICE.

CHARLES A. BOYLE, OF BROOKLYN, NEW YORK.

AMUSEMENT DEVICE.

Application filed May 12, 1922. Serial No. 569,272.

To all whom it may concern:

Be it known that I, CHARLES A. BOYLE, a citizen of the United States, residing at Brooklyn, in the county of Kings and State 5 of New York, have invented certain new and useful Improvements in Amusement Devices, of which the following is a full, clear, and exact description, such as will enable others skilled in the art to which it 10 appertains to make and use the same.

This invention relates to amusement devices.

One object of the invention is to provide an improved form for an apparatus of this 15 character which is responsive to air currents.

Another object is to provide a simple device of this character which is positive in operation, inexpensive to manufacture, and 20 attractive by virtue of its appearance and method of operation.

Other objects will be in part obvious and in part pointed out hereinafter.

The invention accordingly consists in the 25 features of construction, combinations of elements and arrangement of parts which will be exemplified in the construction hereinafter set forth, and the scope of their application will appear in the appended 30 claims.

One embodiment which the invention may assume in practice is illustrated in the figure of the drawing which represents a miniature aeroplane held captive on a standard and adapted to move up and down thereon under the influence of air currents directed therat.

Referring more specifically to the drawing, there is provided a standard or guide 40 member 1 which may be rigidly supported by a wide bottomed base 2 by means of which it may be placed on any relatively flat supporting surface. Preferably standard 1 is placed vertically and includes a 45 straight cylindrical rod having a smooth exterior surface to avoid friction between it and the object for which it performs the function of a guide.

This object illustrated as a miniature 50 aeroplane of the biplane type is provided with wings or vanes 3 and 4 spaced apart by upright members 5; and a rudder having suitable horizontal vanes 6 and 7 formed by rearward extensions of vanes 55 3 and 4 respectively, and a vertical vane 8 which may extend between vanes 6 and 7.

In order that the miniature may further resemble a real aeroplane it may be provided with suitable characteristic appurtenances such as a propeller 9 pivotally mounted on 60 vane 3.

Vanes 3 and 4 may be provided with rearward extensions 10 downwardly inclined therefrom and serving as a means to lift the aeroplane when acted upon by horizontal air currents. The rudder has similar 65 extensions 11 of vanes 6 and 7 tending to balance the aeroplane.

The aeroplane above described is adapted to move longitudinally of standard 1 in 70 response to air currents directed therat, and is also pivotally connected to said standard. While so moving it is also desirable to maintain the vanes in operative position on the standard with respect to the air currents. Any suitable bearing connection may 75 be employed for this purpose, and to this end one or more of the vanes are pierced to pass the standard 1 therethrough. The holes 12 so formed in vanes 3 and 4, as shown in 80 the drawing, prevent any considerable tipping of the device since they are spaced apart at a substantial distance.

In order to be influenced by an air current of moderate velocity it is preferable 85 that the aeroplane be constructed of light material such as pasteboard or stiff paper. Any suitable material may however be used and the character of such material will vary 90 with the conditions under which the device is to operate. If employed as a shop window display device, the apparatus may be made of more expensive and durable material, whereas as a child's toy it is more desirable to make it of cheaper construction. 95

A stop member 13 in the form of a ball is attached at the end of standard 1 to limit the longitudinal motion of the aeroplane thereon and also to hold it captive.

The source of the air currents above referred to may be of any desired character. One such source may be an electric fan (not shown) which oscillates slightly to cause a corresponding rising and lowering of the aeroplane which will attract more attention 100 thereto than if held at a fixed altitude by a steady current of air.

Thus by the above construction are accomplished among others, the objects above referred to.

As many changes could be made in the above construction and many apparently 110

widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. In a device of the character described, in combination, a vane having downwardly-extending lifting surfaces, an extension forming a part of said vane and having its inner end disposed at a point short of said lifting surfaces, a second vane at the outer end of said extension, and a downwardly-extending lifting surface forming a part of said second vane.

2. In a device of the character described, a single sheet of material providing a vane,

downwardly-extending portions at the rear edge of said vane furnishing lifting surfaces, an extension forming a part of and projecting from the rear edge of said vane and between said downwardly-extending portions, and a second vane at the outer end of said extension and having its rear edge bent downwardly to provide a lifting surface.

3. A device of the character described, including, in combination, an upright, two sheets of material, each presenting a vane formed with an opening through which said upright is adapted to extend, downwardly-projecting portions at the rear edge of said vane to furnish lifting surfaces, an extension forming a part of said vane and projecting rearwardly from the rear edge thereof and said lifting surfaces, a second vane at the rear end of said extension, and means between said sheets of material for maintaining the same in spaced relationship and against movement with respect to each other.

In testimony whereof I affix my signature.

CHAS. A. BOYLE.
